UNITED STATES PATENT OFFICE.

DEAN A. BECKWITH, OF NEW YORK, N. Y.

FILE OR DRAWER LOCK.

SPECIFICATION forming part of Letters Patent No. 683,835, dated October 1, 1901.

Application filed December 4, 1900. Serial No. 38,682. (No model.)

To all whom it may concern:

Be it known that I, DEAN A. BECKWITH, a citizen of the United States, and a resident of the city of New York, borough of Manhattan, in the county and State of New York, have invented a new and Improved File or Drawer Lock, of which the following is a full, clear, and exact description.

The invention relates to casings for containing files, drawers, and the like; and its object is to provide a new and improved file or drawer lock arranged to securely lock all the files or drawers in position in the casing at the same time or to unlock all the files or drawers for convenient removal of the same at once to give access to their contents.

The invention consists of novel features and parts and combinations of the same, as will be fully described hereinafter and then pointed out in the claims.

A practical embodiment of the invention is represented in the accompanying drawings, forming a part of this specification, in which similar characters of reference indicate corresponding parts in all the views.

Figure 1 is a sectional perspective view of the improvement as applied to a casing containing document-files. Fig. 2 is an enlarged sectional front elevation of the improvement on the line 2 2 in Fig. 3. Fig. 3 is a transverse section of the same on the line 3 3 in Fig. 2. Fig. 4 is a sectional side elevation of one end of the pivoted rock-bar and the bearing thereof, and Fig. 5 is a transverse section of the casing with the lock for the rock-shaft.

The casing A, on which the improvement is applied, is arranged to contain files, drawers, or like devices, and each such device is provided at its rear end with an angular catch C, adapted to be engaged by a lock-bar D, preferably made of inverted-U shape in cross-section similar to channel-iron and provided at its ends with trunnions D', engaging bearings E, secured to the sides of the casing A, as is plainly shown in Figs. 1 and 4, so that the bar D can oscillate on the trunnions to engage the front vertical portion of the lock-bar with the catches C of the several shelves or other devices to lock the same against removal from the casing. By swinging the lock-bar D inward it is moved out of engagement with the several catches, so that the shelves

or other devices become unlocked and can be conveniently removed by the operator from the casing in order to gain access to their contents. In order to impart the desired swinging movement to the lock-bar D, the following device is provided: A vertically-disposed slide F passes through the lock-bar D near the front edge thereof, and on the slide are secured pins F', bearing on the top and bottom of the lock-bar D, so that when the slide is moved up or down a swinging movement is given to the lock-bar as the pins F' carry the lock-bar along during the up-and-down movement of the slide F. On the slide F is formed or secured an enlarged portion F², (see Figs. 2 and 3,) and this enlarged portion is mounted to slide vertically in a suitable bearing G, secured in any desired manner to the casing A. In the enlarged portion F² is formed an elongated slot F³, engaged by the wrist-pin H' of a crank-disk H, secured to the inner end of a lock-shaft I, extending transversely, the inner end being journaled in a bearing G and the outer end on a suitable part A' of the casing A. (See Fig. 1.) On the outer end of the lock-shaft I is secured a handle J under the control of the operator for turning said lock-shaft and causing the crank-disk H to impart an up-and-down swinging motion to the enlarged portion F², and consequently to the slide F, so that the desired rocking motion is given to the lock-bar D for locking or unlocking the shelves B or other devices contained in the casing A. The lock-shaft I is adapted to be locked against movement at the time the lock-bar D engages the catches C, and for this purpose an ordinary lock K is employed, secured to the part A' of the casing and so arranged that the bolt moves in engagement with a flattened portion I' on the lock-shaft I, so as to hold the latter against turning at the time the bolt is shot out.

From the foregoing it is evident that the lock-shaft I engages the slide F and the latter imparts a rocking motion to the lock-bar D, so that the several files or similar devices contained in the casing A are simultaneously locked or unlocked, according to the direction in which the operator turns the handle J.

The device is very simple and durable in construction, is not liable to get out of or-

der, and can be readily applied to any casting and can be cheaply manufactured.

Having thus fully described my invention, I claim as new and desire to secure by Letters 5 Patent—

1. A file or shelf lock, comprising a U-shaped lock-bar hung on pivots and adapted to receive in its channel upward catches on the movable files or shelves, and mechanism 10 for swinging said lock-bar on its pivots.

2. A file or shelf lock, comprising a lock-bar hung on pivots and having parallel downwardly-projecting flanges forming between them a channel adapted to receive upward 15 catches on the movable files or shelves, and mechanism for swinging said lock-bar on its pivots.

3. A file or shelf lock, comprising a lock-bar pivotally mounted to swing about a horizontal axis and provided with a slot running toward said axis, and an operating-bar mounted to slide vertically and extending through the slot of the lock-bar, said operating-bar being provided both above and below the 25 lock-bar, with projections engaging the same.

4. A file or shelf lock, comprising a lock-bar mounted to swing about a horizontal axis and arranged to engage catches on the files or shelves, and a vertically-movable operating-bar extending loosely through the lock-bar at a distance from its axis and having operative engagement with said lock-bar. 30

5. A file or drawer lock, comprising a channel-iron lock-bar adapted to engage angular catches on files or movable shelves, trunnions 35 at the ends of said lock-bar, fixed bearings engaged by said trunnions, a slide having pins engaging the top and bottom of said lock-bar, a crank-disk having its wrist-pin engaging a slot in said slide, and a rock-shaft 40 having a handle and carrying said crank-disk, as set forth.

In testimony whereof I have signed my name to this specification in the presence of two subscribing witnesses.

DEAN A. BECKWITH.
